US00D345606S

United States Patent [19]

Perusek

[11] Patent Number: Des. 345,606

[45] Date of Patent: ** Mar. 29, 1994

[54] MEDICAL GAMMA CAMERA GANTRY

[75] Inventor: Allan J. Perusek, Mentor, Ohio

[73] Assignee: Picker International, Inc., Highland Heights, Ohio

[**] Term: 14 Years

[21] Appl. No.: 617,057

[22] Filed: Nov. 21, 1990

[52] U.S. Cl. D24/159

[58] Field of Search 250/363.08, 492.3; 378/4, 21-27, 91, 208; D24/158, 159

[57] CLAIM

The ornamental design for a medical gamma camera gantry, as shown and described herein.

DESCRIPTION

FIG. 1 is a front elevational view of a medical gamma camera gantry showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a front, right side perspective view thereof;

FIG. 7 is a front elevational view with the upper detector head rotated 45° to the left;

FIG. 8 is a right side elevational view with both rotatably moveable detector heads rotated 45°, facing toward the right; and,

FIG. 9 is a right side elevational view with the rotatable detector head carrying gantry rotated 90° and with the left detector head translated inward.

The bottom of the article is plain and unadorned.

FIG. 1

FIG. 2

FIG. 3

FIG. 4

FIG. 5

FIG. 9

FIG. 6

FIG. 7**FIG. 8**
